UNITED STATES PATENT OFFICE.

JAMES SVANDA, OF MILWAUKEE, WISCONSIN.

CASKET.

1,254,742.

Specification of Letters Patent. Patented Jan. 29, 1918.

Application filed May 18, 1917. Serial No. 169,528.

To all whom it may concern:

Be it known that I, JAMES SVANDA, a citizen of the United States, and resident of Milwaukee, in the county of Milwaukee and State of Wisconsin, have invented new and useful Improvements in Caskets, of which the following is a description, reference being had to the accompanying drawings, which are a part of this specification.

The invention relates to burial caskets.

The invention is more particularly designed to provide a casket in which the body is placed so that it may be viewed during the burial service and after the service be lowered into the casket which is then carried away to the place of burial and placed in the grave.

The invention is further designed to provide in combination with a casket, a body supporting platform which may be raised to display the body and lowered when the casket is closed up.

The invention is further designed to provide a casket with means therein for raising and lowering the body and for lowering the cover of the casket while the body is being lowered.

The invention further consists in the several features hereinafter set forth.

In the drawings:

Figure 1 is a side view of the device embodying the invention, parts being broken away and parts being shown in section;

Fig. 2 is a section taken on the line 2—2 of Fig. 1;

Fig. 3 is a view of one end of the casket taken on the line 3—3 of Fig. 1; parts being broken away and parts being shown in section;

Fig. 4 is a section taken on the line 4—4 of Fig. 1;

Fig. 5 is a section similar to Fig. 4 showing the cover open and in position to be lowered;

Fig. 6 is a section taken on the line 6—6 of Fig. 1;

Fig. 7 is a view taken on the line 7—7 of Fig. 1 when the turning device is removed;

Fig. 8 is a section taken on the line 8—8 of Fig. 7.

In general, the device comprises a casket body provided with a cover, means mounted within the casket for raising and lowering the body, means for actuating said raising and lowering means, means for securing the

cover in open position, and means for lowering the cover when the body is lowered.

In the drawings, the numeral 9 designates the body of the casket which is provided with a hinged cover 10, carrying handles 11 and a spring lock 12 consisting of a spring pressed catch 13 carried by the cover and engageable in a keeper plate 14 on the top edge of the body of the casket, said catch adapted to be unlocked by pressing a button 15, though it will be understood that any suitable form of spring lock may be used to secure the cover in closed position.

The means for raising and lowering the body within the casket comprises a body supporting platform 16 having a head rest 17 and means for raising and lowering the platform. This means comprises a revolvable shaft 18 journaled in the casket and straps 19 upon which the platform is carried. Each of the straps is secured at one end 20 to the shaft 18 thence extends laterally to one side of the casket, thence upwardly on this side through guides 21 and 22 on this side thence across to the other side of the casket beneath the platform 16, thence downwardly on the other side through guides 23 and 24 and thence laterally toward the shaft and secured at its end 25 to said shaft, Figs. 4 and 5. With this construction when the shaft is revolved in a counter-clockwise direction, the straps will be wound up on the shaft 18 and thus shorten the length of the portions of the straps carrying the platform and thus elevate said platform until the straps are drawn level with the upper guides 21 and 23 at which time the platform has reached the upper portion of the casket to display the body, as shown in Fig. 5.

The actuating means comprises a handwheel 26 provided with a hollow shaft 27 having slots 28 therein engaging a pin 29 on the shaft 18 to detachably secure the handle thereto for rotating said shaft and further consists of a brake mounted upon a support 30 carried by the handwheel and detachably secured to one end of the casket. The support is provided with an inwardly extending flange 31 insertible in a recess 32 in the end of the casket and secured thereto by a locking rod 33 passing through a bore 34 in the end of the casket and through an aperture 35 in said flange. The shaft 27 is journaled in the support 30 and carries a grooved brake wheel 36 engageable by a

brake band 37 having its ends 38 extending upwardly through the support and secured thereto by adjustable thumb nuts 39. It will be observed that by screwing down on one 5 of these nuts 39 that the brake band will be brought into frictional engagement with the wheel 36 to retard the movement of the shaft 18 when the body is being lowered. The shaft 27 extends through an aperture 40 in 10 the end of the casket and when the actuating means is removed plates 41 and 42, slidably mounted in the ends of the casket between said end and plates 43 and 44 carried thereby, are moved to cover up the recess 32 15 and aperture 40 respectively, the plate 42 having an air tight fit.

The means for securing the cover in open position consists of a brace rod 45 having a loose pivotal connection at one end with an 20 eye bolt 46 mounted inside one end of the cover and having a pin 47 at its other end engageable beneath a slotted plate 48 in the top of one end of the casket and removable therefrom when desired.

25 The means for lowering the cover when the body is lowered consists of the brace rod 45 previously described which is also provided with a pin 49 and a detachable connection between said brace and the platform 30 16. This connection consists of a T-shaped slot 50 in the platform 16 whereby the pin 47 with the end of the brace may be inserted in the transverse portion of the slot and then moved rearwardly in said slot so that 35 the brace will be held to the platform between the pins 47 and 49 whereby on a lowering of the platform with the body the brace will be moved down and carry the cover down with it to closed position.

Copies of this patent may be obtained for five cents each, by addressing the "Commissioner of Patents, Washington, D. C."

With the construction above described the body is placed in the casket upon the platform which is raised through the mechanism previously described and the cover is turned to open position and secured to display the body. After the burial service, the cover brace is placed in connection with the platform and, with the brake applied, the body is slowly lowered with the cover. The actuating means is then removed and the plates 41 and 42 moved to cover up the recess 32 and aperture 40. Then the casket is carried to the grave.

I am aware that the details of construction herein shown and described are subject to some modification and change and I desire 5 it to be understood that such changes as come within the scope of the appended claim are within the spirit of my invention.

What I claim as my invention is:

The combination, with a casket, of a body 6 supporting platform disposed therein, a shaft within the casket, platform supporting straps mounted within the casket for raising and lowering said platform on the rotation of said shaft, a shaft actuating device comprising a shaft detachably secured to the first named shaft, a brake and a casing for the brake provided with an inwardly extending lug, said casket having an opening 65 therein for receiving said lug, means 70 carried by the casket for engaging the lug to detachably secure the brake-casing thereto, and a plate slidably mounted on the casket adjacent said opening to cover the 75 same when the shaft actuating device is removed.

In testimony whereof, I affix my signature.
JAMES SVANDA.
